FUEL PUMP

Alexander C. Ridland, Rancho Santa Fe, Calif., assignor to Hydro-Aire, Inc., Burbank, Calif., a corporation of California

Application December 27, 1955, Serial No. 555,444

8 Claims. (Cl. 103—113)

This invention relates to liquid fuel pumps and more particularly to a unitary pump unit for aircraft or other applications wherein vapor conditions in the pump can cause flow failures.

Great difficulties have been experienced in pump applications handling liquids at pressures approximating the vapor pressure of the pumped fluid. It is a rather common occurrence in aircraft fuel systems due to extremely wide range of temperature and pressure conditions encountered. The problem is especially acute following resumption of fuel demand after a period of either no flow or reduced flow conditions at high altitude. There are a number of reasons for this. For example, the pump impeller may become submerged in vapor derived from the fuel tank, or generated by heat from the driving motor, or merely from the action of the rotating impeller in liquid at a pressure close to its vapor pressure, or a combination of these and other factors. This condition isolates the impeller from liquid and prevents it from exerting a propelling force thereon until the vapor can be condensed or expunged from the pump in some manner. Even a moment's delay in rectifying the condition can be fatal if it occurs when the pilot expects and requires full and instantaneous resumption of fuel flow to meet an emergency situation.

The present invention has been found to provide a simple yet fully reliable means of safeguarding against flow failure due to the presence of vapor or gas in the pump impeller chamber. This is done by the simple expedient of maintaining a minimum flow of liquid through the pump inlet and past the entrance end of the pump impeller at all times including periods when the discharge outlet proper is throttled or even closed. This continuous circulation of fuel through a short circuit in parallel with the main fluid circuit not only serves to maintain the impeller below vapor generating temperatures but keeps the pump inlet purged of vapor so that the impeller blades are always in contact with liquid and exerting a propelling force thereon.

Accordingly, it is an object of the invention to provide a pump design which is not subject to flow failure due to vapor lock under any operating conditions in which liquid can reach the pump inlet.

Another object is the provision of a simple, rugged fuel pump having means for circulating a predetermined amount of fuel past the fluid propelling element even when little or no fuel flow is permitted from the pump outlet.

Yet another object is the provision of a power-driven pump unit designed for use while submerged and having special provision for safeguarding the same against failure due to gas or vapor pockets within the pumping chamber.

These and numerous other objects and advantages will become readily apparent from the following detailed specification of an illustrative embodiment taken in connection with the accompanying drawings, wherein:

2

Figure 1 is a vertical sectional view taken upon the line 1—1 of Figure 2 showing my pump assembly extending upwardly into a fuel tank from its bottom wall; and

5 Figure 2 is a fragmentary sectional view along line 2—2 of Figure 1 showing the disposition of my vapor purge ports opening through the wall of the pump inlet adapter.

Referring to the drawings it will be seen that my 10 pump assembly includes a generally tubular main housing 10 enclosing an electric driving motor of any suitable sealed type for submerged operation and directly coupled to a liquid fuel pump generally designated 12 disposed at the opposite lower end thereof. It will of course be 15 appreciated that an air turbine, a hydraulic motor or any other known means of converting transferable energy to mechanical motion may be used in lieu of the electric motor if so desired.

The lower end of motor shaft 14 extends through 20 a fluid seal 27 housed within a cavity 23 of the cupped partition 24 held assembled to the top of the pump body by screws 22. An O-ring 26 is seated in an annular groove in ring 24 to form a fluid seal with the motor casing. The mechanical fluid seal 27 provides a fluid 25 seal between the motor chamber and pump chamber at the rotating shaft 14.

As here shown, the pump impeller has a generally 30 conical hub fastened to the lower end of shaft 14. Spirally encircling its exterior is a continuous convoluted impeller blade 29 projecting perpendicularly from the surface of hub 28 and extending substantially from the tip to the base end in the manner illustrated in Figure 1. Its outer free edges terminate in closely spaced relation to the conical inner surface 30 of the 35 inlet adapter 31. This adapter has an outwardly-flanged rounded inlet 32 suitably spaced above the combination cover and mounting plate 33 for the unit. The periphery 34 of the plate 33 projects appreciably beyond outer side walls of casing 10 to provide a mounting flange 40 adapted to seat against the edges of an inlet opening 35 cut in the bottom wall 36 of fuel tank 37.

Pump inlet adapter 31 is provided with a peripheral flange 38 which may be secured to the lower end of housing 10 by screws 39. Housing 10 has a number of 45 supporting legs 40 spaced apart so as to provide large area fuel inlet openings 41 about the base of the unit. These openings are preferably guarded by a screen or grille work 42.

The means for preventing convoluted pump chamber 50 43 from becoming clogged with quiescent gas or vapor preferably comprises a series of small diameter ports 44 extending through wall 31 of the inlet adapter at a point generally opposite the lowest convolution of impeller blades 29. Most effective results are obtained by 55 locating the axes of these ports generally tangential to the interior face 30 of the inlet adapter. In consequence, the gas and liquid being contacted and propelled by the lowest convolution of the impeller 28 is highly effective in returning a certain quantity of the fluid 60 being pumped back into the tank or supply source through bypass ports 44.

During normal operation of the pump, the main body 65 of the fluid contacted by the impeller is propelled into the volute-shaped pump discharge chamber 45 which opens through the side wall of housing 10 at a point directly behind shaft 14 and generally indicated by dotted lines in Figure 1. While not so shown in the present drawings, it will be understood that the outlet from chamber 45 is connected to a fuel line leading to a point of use such as the engine of an aircraft.

70 The operation of my pump will be quite obvious from the foregoing description. Under normal operating con-

ditions liquid fuel in which the entire pump unit is preferably submerged enters through the grille 42 and passes upwardly through inlet 32. The impeller blades 29 driven by motor 11 propel the major portion of the fuel entering inlet 32 upwardly and outwardly into the discharge convolute 45. However, a relatively small percentage is discharged outwardly through purge openings 44. Any vapor present in the purged fuel will rise upwardly about the sides of the pump housing, whereas liquid portions will recirculate back into the pump inlet. The capacity of the bypass ports is so designed that the fuel so purged does not interfere with the maximum fuel requirements of the system supplied by the pump.

Let it be assumed that the fuel demand ceases and that the outlet to chamber 45 is closed or substantially so. Let it also be assumed that the fuel surrounding the pump is close to the vapor pressure. Under these conditions the rotation of the pump impeller together with the heat generated by the motor will cause considerable fuel to be vaporized and to collect in the pump inlet adapter. Eventually the entire chamber would become filled with the vapor were it not for the action of the lower convolution of the impeller in circulating fuel through bypass ports 44. But even though the entire upper portion of the pump chamber becomes filled with vapor the lower end will be flooded with liquid circulating through the bypass ports. This circulation will not only maintain the lower end of the pump and its inlet free of vapor, but it will keep a stream of liquid flowing past the impeller 28 to cool the same. This cooling effect plus the increased pressure caused by the impeller may even result in the condensation of the vapor collected in the upper portion of the pump chamber.

In consequence of the foregoing and upon the reopening of the fuel valve, even though this opening be to a limited extent, the lower turn of the impeller, submerged as it always is in liquid, will be immediately effective in propelling fuel upwardly to purge the upper portion of the chamber of vapor as well as to circulate fuel to the point of use. Hence, the pump is effective to resume fuel flow at any rate desired in a negligible period of time.

From the foregoing it will be readily apparent that the present invention provides an unusually simple yet highly effective construction for assuring fuel flow under the most extreme and exacting operating requirements and despite conditions tending to create vapor lock conditions within the pump chamber. The design is not only capable of positively purging the pump of any vapor pockets but it operates in a manner greatly discouraging the conditions conducive to their formation.

Having now described my invention and in what manner the same may be used, what I claim is new and desire to protect by Letters Patent is:

I claim:

1. A submerged fuel pump adapted for mounting in a liquid fuel tank comprising, a casing defining an upwardly and outwardly flaring volute and including an inlet adapter, said adapter having an axial inlet at its lower end in lateral communication with liquid fuel surrounding said pump and a peripheral outlet at its upper end for connection with a point of liquid fuel delivery, a power-driven outwardly flaring conical impeller rotatably supported in said inlet adapter having spirally arranged blade means thereon for propelling fuel through said inlet and discharging the same from said outlet, and a plurality of fuel outlet ports opening outwardly through the side wall of said inlet adapter radially opposite said impeller blade means at points closely adjacent said fuel inlet whereby vapor present in the inlet area of said pump is discharged through said fuel ports so that liquid fuel can contact said blade means and be propelled thereby toward said fuel outlet.

2. A submerged fuel pump as defined in claim 1 wherein said fuel outlet ports have their axes disposed

generally tangentially to the side wall of said inlet adapter whereby said spirally arranged impeller blade means operate with maximum efficiency in purging the volute chamber of vapor.

3. A submerged fuel pump as defined in claim 1 wherein in the portion of said inlet adapter enclosing said impeller is of frustoconical configuration with said fuel inlet at the small diameter end thereof, said impeller having a conical hub provided with thin spirally arranged blade means projecting substantially normal to the surface of said hub from the tip toward the base end thereof, and said fuel outlet ports being located close to but spaced inwardly from the inlet end of said impeller.

4. A submerged fuel pump as defined in claim 1 wherein in said pump includes a base plate connected thereto but lying in a transverse plane spaced below the inlet to said inlet adapter and adapted to support said pump inwardly of but close to the bottom wall of a fuel tank.

5. In combination, a compact fuel pump assembly adapted for use while submerged in fuel and capable of producing substantially instantaneous fuel flows even after extended periods of operation with flow from the delivery outlet substantially shut off, said pump assembly including a tubular housing having an electric motor sealed within its upper end and a frustoconically-shaped inlet adapter formed in its opposite end, an impeller housed in said inlet adapter having a conical hub supporting spirally arranged blade means substantially normal to said hub and terminating in closely spaced relation to the inner wall of said inlet adapter, means coupling said impeller to said motor, said inlet adapter having a central downwardly-opening inlet communicating laterally with fuel in which said pump is submerged, and means preventing cavitation at the inlet end of said impeller due to the formation of a pocket of fuel vapor in said inlet adapter, said cavitation prevention means including fuel outlet ports opening outwardly through the inlet adapter side wall on a plane transversing the inlet adapter near the small diameter end thereof whereby said impeller continues to circulate the fuel outwardly through said ports even during zero flow conditions in the pump circuit proper and serving to maintain said impeller cool and to bleed vapor from the inlet adapter.

6. A fuel pump for use in fuel supply lines of aircraft subject to widely fluctuating temperature and pressure conditions likely to cause the presence of substantial percentages of fuel vapor in the streams being handled by the pump, said pump having a casing forming an inlet adapter with a downwardly-opening central fuel inlet and a peripherally disposed outlet thereabove, said inlet having a large area fuel supply passage means opening laterally into a fuel supply tank, outwardly flaring conical bladed impeller means rotatably supported in said inlet adapter and discharging generally axially and peripherally into said outlet thereabove, an electric driving motor coupled to said impeller, means for assuring continuous flow of fuel through the inlet of said pump even during periods in which said outlet is blocked for the purpose of cooling said impeller and safeguarding against the same becoming submerged in fuel vapor, said means comprising a series of tangential vapor outlet openings of restricted capacity leading back into the fuel supply through the wall of said inlet adapter at a level spaced between the inlet and outlet thereof, the combined capacity of said tangential vapor outlet openings being appreciably less than the main fuel outlet at the upper end of said pump chamber.

7. A fuel pump as defined in claim 6 including means for supporting said pump interiorly of a fuel tank from the bottom wall thereof with the pump inlet lying in a plane substantially coincident with the bottom of the tank.

8. A fuel pump as defined in claim 6 wherein the inner ends of said restricted capacity fuel openings are directly

opposite and swept by the blade means at the lower end of said impeller action tending to circulate fuel through said restricted openings whenever said impeller is operating, said impeller having a conical hub and the blade means carried thereby being substantially normal to the conical surface of said hub and effective in throwing entrained fuel vapor outwardly for escape through said restricted openings back into the fuel tank.
